CLAIM

The ornamental design for a body shaping sweatpants, as shown and described.

DESCRIPTION

FIG. 1 is a front perspective view of a body shaping sweatpants design showing my new design.

FIG. 2 is a front view thereof.

FIG. 3 is a rear view thereof.

FIG. 4 is another front perspective view thereof; shown with the pants separate.

FIG. 5 is a front view thereof.

FIG. 6 is a rear view thereof.

FIG. 7 is a front view of thereof, shown with the waistband separate; and,

FIG. 8 is a rear view thereof.

The shade lines shown in the drawings are utilized to illustrate the surface contours of the body shaping sweatpants design. The broken lines shown in the drawings illustrate sewing thread and form part of the claimed design.

1 Claim, 8 Drawing Sheets
